SKI CONSTRUCTION

Irving P. Simonsen, Glendale, and George R. Hannan, Los Angeles, Calif., assignors to Axlocksen Ski Products, Inc., Beverly Hills, Calif., a corporation of California

Application October 24, 1938, Serial No. 236,638

7 Claims. (Cl. 280—11.13)

Our invention relates to improvements in skis and the like with particular reference to brake means for preventing rearward movements of skis.

Climbing snow-clad slopes with conventional skis is unduly tiring because a ski slides back at each forward stride of the wearer. To minimize such rearward ski movement various automatic braking attachments have hitherto been suggested in the art, most of the devices incorporating a pivoted brake member that swings downward into engagement with the snow on backward movement of the ski and trails over the surface of the snow on forward movement of the ski. The present invention is directed to an improved braking means of this general type.

One object of the invention is to provide a brake blade for the rear of a ski that will penetrate the snow and withdraw therefrom with minimum displacement of the snow.

Another object is to provide a blade that in effective disposition will react to rearward force from the ski by directing a force component downward against the deeper layers of snow beneath the ski.

A feature of our invention is the conception that these three objects may be achieved by employing an arcuate brake blade having a configuration approaching the curvature of the downward path traversed by the rear end of the ski in hill climbing. It is to be noted that the forward portion of the ski normally engages the snow first on a forward stride uphill and then serves as a fulcrum about which the ski rotates downwardly.

A third object of our invention is to provide a relatively light brake blade that in one position will engage the snow with maximum effectiveness and in another position will trail over the snow with minimum contact therewith as the ski is moved forward. A fourth object in mind is to provide a ski brake which in its ineffective or upper position will offer minimum frictional resistance to the normal lateral skidding of the ski that is characteristic of turning maneuvers. A feature of our invention is that the above third and fourth objects may be attained by making the brake blade V-shaped in transverse section. The V-shaped blade may be made relatively thin since diverging portions of the blade support each other. When such a blade is in effective snow-engaging position, the two diverging wings provide exceptional purchase to oppose rearward movement of the ski, and, on the other hand, when the blade is trailed behind

the ski on forward movement of the ski, contact with the snow tends to be restricted to the point of the V at the rear end of the blade. When the ski is skidded sidewise on a turn, the trailing blade presents an upwardly inclined leading edge to cause the blade to ride lightly over the snow with minimum resistance. Any substantial resistance at such a time invites an accident by disturbing the wearer's balance.

Another object in mind is to favor penetration of the snow by such expedients as cutting back the rear end of the blade from the center line, by beveling the rear edge, and by "scalloping" the end of the blade to form a series of rounded blade portions.

A further object is to provide a blade having an effective downward position sufficiently inclined to the rear to cause the blade to swing upwardly by inertia when the wearer makes a square-jump turn. In other words, we propose to have the center of gravity of the blade rearward of the blade's pivot-axis when the blade is in its lowermost position.

Another object of our invention is to provide an automatic latch for holding the blade elevated above the snow when desired. In the preferred form of our invention a fractional latch is employed, adapted to engage the blade automatically whenever the blade is raised to a predetermined angle, the latch being adapted to release the blade when the blade is jarred downwardly in a relatively violent manner by the wearer.

A still further object of our invention is to provide shock-absorbing means to cushion the downward movement of the brake blade and to protect the end of the ski from the blade. A feature of the preferred form of our invention in which yielding means is employed to urge the blade downwardly is that the shock-absorbing means resiliently opposes said yielding means when the blade is in its downward position whereby on a square-jump turn the shock-absorbing means initially works with the inertia of the blade to raise the blade in opposition to said yielding means.

In achieving the various objects recited above, we propose to incorporate our invention in a device to be sold separately as a ski accessory, the device being adapted for ready attachment to conventional skis.

The above and other objects will be apparent in the detailed description to follow, considered with the accompanying drawing.

In the drawing:

Fig. 1 is a side elevation on a reduced scale of a ski incorporating our invention;

Fig. 2 is a plan view of the rear end of a ski 5 showing an embodiment of our invention mounted thereon, the blade being in its effective position;

Fig. 3 is a rear elevation of a ski showing our invention with the blade in effective position;

10 Fig. 4 is a transverse section of the blade taken along the line 4-4 of Fig. 3;

Fig. 5 is a vertical longitudinal section of the blade taken along the line 5-5 of Fig. 3;

15 Fig. 6 is a fragmentary section through the hinge of the blade with the blade in latched position; and

Fig. 7 is a perspective view of a latch member employed in the preferred form of our invention.

20 Our invention includes a bracket or hinge member generally designated 10 by means of which a brake blade generally designated 11 may be mounted for pivotal movement on the rear end of a ski 12. It is contemplated that both the blade and the bracket will be made of aluminum or similar light but sturdy material.

25 The bracket 10 has a forward base portion 14 adapted to overlie the upper surface of the ski, which base portion may be U-shaped in plan, as shown in the drawing. This base portion 14 is adapted to be attached to the ski 12 by a plurality of screws, for example, a forward pair of screws 15 and a rearward pair of screws 16. The bracket 10 has a pair of spaced bracket arms 18 overhanging the rear end 19 of the ski, the bracket arms carrying a pintle or hinge pin 20.

30 In the preferred form of our invention shock-absorbing means are provided to resiliently limit the downward movement of the blade 11. Such shock-absorbing means may comprise, for example, a pair of angular leaf springs 22 inserted between the ski and the bracket 10 in engagement with the rearward screws 16, the ends of the leaf springs extending downward in spaced relation to the rear end 19 of the ski. These 35 leaf springs are designed not only to protect the end of the ski from impact by the blade but also to cooperate with the blade in a manner to be described later.

35 The blade 11 is rotatably connected to the bracket 10 by a pair of ears 25 engaging the hinge pin 20 inside of the bracket arms 18. In the preferred form of our invention the ears 25 constitute portions of a pair of reinforcing ribs 26 integral with the body of the blade 11, each 40 of the ribs providing a shoulder 27 to cooperate with the corresponding leaf spring 22.

45 As viewed in side elevation, the blade 11 in the preferred form of our invention is of arcuate configuration with the center or centers of curvature well forward whereby the blade approximates the curvature of the path traversed by the rear end of the ski in its downward movement as the wearer of the ski steps forward in climbing a slope. The forward end of the ski makes initial 50 contact with the snow and causes the rear end of the ski to approach the snow in a path of arcuate character. A straight flat blade penetrating the snow substantially endwise in such a curved path would displace more snow than necessary, the hole in the snow created by the penetration being substantially larger in transverse section than the blade. If, however, the rear end of the ski follows a perfect circle in its 55 downward movement and the curvature of the blade coincides with the circle, the blade will 60

penetrate the snow with substantially no more displacement than represented by the thickness of the blade. It is recognized, of course, that there is no mechanical precision in the arcuate movement of the rear end of the ski, but nevertheless forming the blade with an arcuate configuration will minimize snow displacement to a substantial and significant extent. 5

We believe from our experiments that the braking action of the blade is reduced to an undesirable extent if the blade has a curvature for moving into and out of the snow with minimum snow displacement. We prefer, therefore, a blade of less than the curvature that is optimum for snow displacement. The preferred curvature 15 indicated in the drawing will cause a slight initial forward displacement of the snow at the upper portion of the blade as the ski is moved forward with the blade buried in the snow. Because our blade is V-shaped it readily noses into 20 the snow to the slight degree required with no significant resistance to the forward movement of the ski. On the other hand, a blade that is flat or rectilinear in cross-section requires appreciable force to make the necessary initial snow 25 displacement. In other words, a buried blade that is not V-shaped in cross-sectional configuration would provide initial resistance to the forward stroke of the ski to an undesirable extent, the resistance being noticeable because not 30 encountered in the use of conventional skis.

A further advantage of the curved configuration of the blade is that when the blade in its effective position is pressed backward by the 35 ski, the pressure of the blade against the snow includes a downward inclined component force as indicated by the arrow 28 in Fig. 5. This feature is important because such a component is directed towards the ground or the lower compact layers of snow providing relatively great 40 resistance to rearward movement of the blade.

In the preferred form of our invention shown in the drawing, the blade is V-shaped in transverse section and, as may be understood by reference to Fig. 4, the blade by virtue of such 45 shape in effect comprises two diverging wings 30. The V-shaped configuration of the blade not only contributes strength but also is significant in the functioning of the blade. In the first place, we have found that the V-shaped configuration increases the effectiveness with which the blade engages the snow. When a straight flat blade in effective position is pressed backward against the snow, the snow tends to escape around the edges of the blade, only a relatively narrow 50 and short body of snow being compressed by the rearward blade movement. In a blade providing diverging wings, however, the tendency of the snow to escape around the edges of the blade is minimized, and backward movement of the 55 blade against the resistance of the snow tends to press the snow into a compact tapering body having the configuration indicated by the dotted line 31 of Fig. 4. Another functional advantage of the V-shaped configuration is that such a 60 configuration provides a point 33 on the rear end of the blade. When the blade is dragged forward by the ski, the blade being in the trailing disposition indicated at 34 in Fig. 1, the contact of the 65 blade with the snow tends to be restricted to this point especially if the snow is packed or has a crust.

To favor penetration of the snow by the blade, especially when the snow has a resistant crust, the rear edge of the blade may be cut back from 70 75

the center line of the blade so that the center of the blade will penetrate first. In addition, we prefer to bevel the edge of the blade to form a cutting edge, and to notch or "scallop" that edge 5 to form a central curved blade portion 35 flanked by curved portions 36 and 37 disposed to penetrate the snow successively.

While the blade 11 may be designed to have an effective inherent tendency to swing downward into effective braking position by virtue of its own weight, we prefer to incorporate in the pivotal mounting of the blade yielding means to urge the blade continuously downward. For example, such yielding means may comprise a 15 helical spring 48 around the hinge pin 20, one end 41 of the spring being anchored in a complementary aperture in the blade and the other end 44 of the spring being anchored in a second aperture in the bracket 10.

The automatic latch that may be incorporated in the preferred form of our invention may be of any character but preferably will operate by frictional engagement whereby the latch will automatically engage the blade whenever the 25 blade is raised to a desired latching angle and whereby the latched blade may be released at the will of the operator by simply stomping the ski to jar the blade downwardly. We have found that a latch of the desired operating characteristics 30 may be had by employing a latching cam 45 of spring metal having the configuration shown in Figs. 6 and 7. The latching cam has a stem 47 apertured to receive a rivet 48 by means of which the latching cam is mounted on the inner 35 face of one of the blade ribs 26. The latching cam has an aperture 49 embracing the hinge pin 20, the forward end of the latch having a normal flexure yieldingly departing from the plane of the stem 47. The forward end of the latching cam has a flange 50 having a gradually inclined 40 portion 51 and a relatively steep shoulder 52. For latching operation the cam may be disposed, for example, to engage the end portion 44 of the wire spring 40. To protect the spring from 45 wear, however, we prefer to provide a small flanged sleeve 54 embracing the wire at the point of engagement. Wear will be minimized and release of the latch facilitated if this sleeve is rotatable on the wire.

The operation of our invention will be clear 50 from the foregoing disclosure. In skiing down hill or sliding on the level, the blade may be either in latched position as shown in dotted lines in Fig. 5, or may be in trailing disposition 55 as shown in dotted lines at 34 in Fig. 1.

If the blade is in trailing position, frictional 56 resistance engendered by the end of the blade alighting on the snow will be insignificant because of the point contact. On making a square-jump turn, the hinge spring 40 will tend to swing the 60 blade downwardly. Because of inertia, however, the sharp downward movement of the ski at the end of the square-jump turn will cause the blade to swing upward towards the trailing position. 65 It is also to be noted that centrifugal force incidental to the turn will assist the upward movement of the blade.

If the blade is at latched position at the beginning 70 of a climb, the wearer may release the blade to the desired trailing position by simply stomping the ski to jar the blade downwardly. In climbing a slope, the ski blade alternates between trailing position and effective position, moving to trailing position as the ski slides forward and automatically swinging to effective posi-

tion whenever the ski starts to move rearwardly, the rearward movement being quickly and effectively terminated by the blade. At the end of a climb the wearer may "cock" the blade into latched position by simply raising the forward 5 end of the ski to an angle and pressing the blade downwardly and forwardly against the snow.

We have described a preferred form of our invention in specific detail for the purpose of this disclosure and to illustrate the principles involved. It will be readily apparent to those skilled in the art that various changes and modifications may be made without departing from the essence of our invention, and we reserve the right to all such changes and modifications that properly come within the scope of our appended claims.

We claim as our invention:

1. A ski accessory comprising: a blade; means for hingedly mounting the blade on the rear of a ski to swing between a downward snow-engaging position and an upper position out of the snow, said blade being V-shaped in transverse section whereby back pressure of the blade against the snow will compact a relatively long tapering body of snow, and whereby the blade when dragged forward along the snow will tend to contact the snow only at a restricted central area at the tip of the blade; and yielding means to urge said blade towards its downward position.

2. A ski having: a blade; means hingedly mounting the blade on the rear of the ski to swing between a downward snow-engaging position and an upper position out of the snow, said blade being of arcuate configuration in side profile to minimize snow displacement when moving endwise into or out of the snow, said blade being V-shaped in transverse section whereby back pressure of the blade against the snow will compact a relatively long tapering body of snow; and yielding means to urge the blade to its downward 40 position, the end of said blade being cut back from the center line of the blade and being beveled to favor snow penetration.

3. A ski accessory comprising: a blade; means for hingedly mounting the blade on the rear of a 45 ski to swing between a downward snow-engaging position and an upper rearwardly inclined position out of the snow, said blade being of arcuate configuration in side profile to minimize snow displacement when moving endwise into or out of the snow, said blade being V-shaped in transverse section whereby back pressure of the blade against the snow will compact a relatively long tapering body of snow; and a latch to releasably hold said blade at said upper position, said latch 50 being adapted to be opened by a relatively severe downward jar.

4. A ski having: a blade; means hingedly mounting the blade on the rear of the ski to swing between a downward snow-engaging position and an upper position out of the snow, said blade being of arcuate configuration in side profile to minimize snow displacement when moving endwise into or out of the snow; yielding means to urge said ski towards said downward position; and shock-absorbing means on the rear end of the ski to cushion the downward movement of the blade.

5. A ski having: a blade; and means hingedly mounting the blade on the rear end of the ski to 70 swing between a lower snow-engaging position and an upper position out of the snow, said blade being V-shaped in transverse section with a forwardly pointed apex whereby in the lower position of the blade back pressure of the blade against 75

the snow will compact a relatively long tapering body of snow, and whereby in the upper position of the blade the apex of the blade will drag on the snow.

- 5 6. A ski having: a blade; and means hingedly mounting the blade on the rear end of the ski to swing between a lower snow-engaging position and an upper position out of the snow, said blade having the shape in transverse section of a forwardly pointed V with rectilinear legs whereby in the lower position of the blade back pressure of the blade against the snow will compact a relatively long tapering body of snow, and whereby in the upper position of the blade the apex of the blade will drag on the snow.
- 10 15. A ski accessory comprising: a blade; and

means for hingedly mounting the blade on the rear of a ski to swing between a downward snow-engaging position and an upper position out of the snow, said blade being of arcuate configuration in side profile and in its downward position curved forward to minimize snow displacement when moving endwise into or out of the snow, said blade being V-shaped in transverse section with the apex of the V forward whereby in its downward position back pressure of the blade against the snow will compact a relatively long tapering body of snow, and whereby in the upper position of the blade the apex of the blade will drag on the snow.
